[57] CLAIM

The ornamental design for a menu control panel for a universal remote control unit, as shown and described.

DESCRIPTION

FIG. 1 is a front and upper left perspective view of a menu control panel for a universal remote control unit showing my new design. The broken line showing is included for the purpose of illustrating environmental elements only and forms no part of the claimed design; FIG. 2 is right side elevational view thereof, the left side elevational view thereof being a mirror image; FIG. 3 is a rear elevational view thereof; FIG. 4 is a top plan view thereof; FIG. 5 is a bottom plan view thereof; FIG. 6 is a front and upper left perspective view of a menu control panel for a universal remote control unit showing a second embodiment of my new design. The broken line showing is included for the purpose of illustrating environmental elements only and forms no part of the claimed design; FIG. 7 is right side elevational view thereof, the left side elevational view thereof being a mirror image; FIG. 8 is a rear elevational view thereof; FIG. 9 is a top plan view thereof; and, FIG. 10 is a bottom plan view thereof.
